UNITED STATES PATENT OFFICE.

JOHN F. O'CONNOR, OF CHICAGO, ILLINOIS, ASSIGNOR TO W. H. MINER COMPANY, OF CHICAGO,
ILLINOIS, A CORPORATION OF ILLINOIS.

FRICITION DRAFT-RIGGING FOR RAILWAY-CARS.

No. 922,619.

Specification of Letters Patent.

Patented May 25, 1909.

Application filed January 7, 1909. Serial No. 471,060.

To all whom it may concern:

Be it known that I, JOHN F. O'CONNOR, a citizen of the United States, residing in Chicago, in the county of Cook and State of Illinois, have invented a new and useful Improvement in Friction Draft - Rigging for Railway - Cars; of which the following is a specification.

My invention relates to improvements in draft rigging for railway cars.

The friction draft rigging of the kind to which my invention relates comprises in connection with the draw-bar, draft yoke, draft lugs and followers, a longitudinally movable friction shell having a transverse partition therein, a preliminary compression follower and spring on one side of said transverse partition and a main spring and longitudinally movable friction blocks on the opposite side of said partition, a wedge between said friction blocks, and anti-friction rollers interposed between the inclined or wedging faces of the wedge and friction blocks, one on each side of the wedge and each roller having a rolling action on both the wedge and friction block between which it is interposed, the wedge and friction blocks having coöperating shoulders to keep the rollers in proper transverse alinement. And my present improvement consists in combining with these parts a roller holder or centering device to keep the rollers from slipping endwise and thus engaging and binding at their ends against the interior surface of the friction shell and thus interfering with the proper operation of the other devices. This roller holder or centering device preferably consists of a bar adapted to fit between the point or inner end of the wedge and the adjacent friction block, and provided with a pair of disk like projections adapted to embrace the anti-friction roller and keep it in place longitudinally. The roller holder bar is preferably furnished near its middle with a projection or lug to give it a restricted bearing or contact with the wedge.

In the accompanying drawing forming a part of this specification, Figure 1 is a side elevation partly in central, vertical section of a friction draft rigging embodying my invention. Fig. 2 is a vertical cross section on line 2—2 of Fig. 1 and Fig. 3 is a detail perspective view of the roller holder or centering device. Fig. 4 is a detail partial horizontal section.

In the drawing, A represents the center sills or draft members of the car to which the draft rigging is applied, A¹ the front sill, B the draw-bar, B¹ the draw-bar yoke, C the side plates or draft members having the customary front, rear and intermediate stops or draft lugs for the followers D D¹ to abut against.

E E¹ are the main draft rigging springs, E² the preliminary compressing spring, F the longitudinally movable friction shell or case, having an internal friction face f and provided with an integral transverse partition or web f¹ against which one end of the main springs E E¹ abut, and against which one end of the preliminary compression spring E² also abuts. The main springs E E¹ abut at their other end against the friction blocks or shoes F¹, the springs E E¹ being thus interposed between the friction shoes and friction shell. The preliminary-compression follower D² is interposed between the rear follower D¹ and the preliminary compression spring E².

G is the wedge and g g the anti-friction rollers interposed between the inclined faces g¹ of the wedge and the inclined faces f² of the friction shoes or blocks F¹ F¹. The wedge G also has stop shoulders g² coöperating with similar stop shoulders f³ on the friction shoes to hold the anti-friction rollers in place. The friction shoes or blocks F¹ are provided with shoulders f⁴ to engage the lugs h of the connecting device or rod H which extends longitudinally through the main springs E E¹ and through the transverse partition web f¹ of the friction shell F and engages the preliminary compression follower D² to which it is connected by a threaded stem h¹ and adjusting nut h². The connecting device or rod H is further provided with an integral stop shoulder or web h³ adapted to engage the transverse partition f¹ of the friction shell so that this one connecting device or rod H will serve to hold both the preliminary compression spring E² and the main springs E E¹ under an initial tension or load as well as to hold all the parts, friction shell, friction blocks, wedge, anti-friction rollers, main springs, preliminary compression spring and preliminary compression follower in proper assembled position and coöperative relation with each other.

To keep the antifriction rollers from slipping longitudinally and bearing or binding and grinding against the interior surface of

the friction shell F at their ends, I combine with the friction shell, friction blocks or shoes and wedge, a roller holder or centering device M preferably consisting of a rectangular bar adapted to fit loosely between the point or inner end g^3 of the wedge and the adjacent inclined face f^2 of the friction block or shoe F¹, and having at its ends a pair of projecting disks or arms m^1 m^2 having flat parallel inner faces m^1 and beveled or inclined outer faces m^2 corresponding somewhat to the curvature of the inner surface of the friction shell F. The roller holder or centering device M is further provided preferably with a central bearing lug or projection m^3 for contacting with the head or inner end of the wedge G.

K is the carry-iron, the same being removably secured to the center sills, draft members by removable bolts K¹. The carry-iron or plate K is furnished with a longitudinal channel K² to receive the lower member of the draft yoke.

In practice, the main draft rigging springs E E¹ are preferably put under an initial compression of about three-eighths of an inch, and the preliminary compression spring under an initial compression of about one eighth of an inch when the several parts are assembled for use. The preliminary compression spring E² is short and adapted to permit about one half inch preliminary cushion movement of the draw-bar before the friction cushioning devices F F¹ are brought into action or forced to frictionally slide in respect to each other.

As in my invention neither the main draft rigging springs E E¹ nor the preliminary compression spring E² act or bear directly against the wedge, and as the wedge has anti-friction rollers on both sides of it, it is thus left free to release or retract after each cushioning movement or compression of the springs, thus insuring a free, easy and perfect release and completely overcoming any tendency of the friction devices to stick or fail in releasing, the roller holder or centering device H coöperating to insure the accomplishment of this result by preventing the lengthwise movement of the rollers and consequent binding thereof against the friction shell.

The initial tension or compression under which the connecting bar or device holds the

springs causes the cushioning mechanism of the draft rigging to remain always of the same proper standard length, notwithstanding the wear that may take place between the friction elements of the cushioning mechanism. The initial tension under which the springs are held should be, as before stated, approximately one half inch, so as to give the draft rigging provision for taking up a large amount of wear between the friction shoes and friction shell, without affecting the normal action of the draft rigging. This initial tension under which the connecting device holds the springs also keeps all the parts in snug and proper engagement with each other.

I claim:—

1. In a friction draft rigging, the combination with a friction shell, of friction shoes within the shell, a spring between the friction shoes and shell, a wedge, anti-friction rollers between the wedge and shoes and a roller holder extending between the friction shoes and having arms embracing the ends of the anti-friction roller, substantially as specified.

2. In a friction draft rigging, the combination with a friction shell, friction shoes and an anti-friction roller, of a holder therefor furnished with arms embracing the ends of the anti-friction roller, substantially as specified.

3. In friction draft rigging having an anti-friction roller acting upon a friction shoe, a holder therefor consisting of a bar furnished with projecting arms embracing the ends of the roller, substantially as specified.

4. In a friction draft rigging having an anti-friction roller acting upon a friction shoe, a holder therefor consisting of a bar furnished with projecting arms embracing the ends of the roller, said arms having flat parallel inner faces, substantially as specified.

5. In a friction draft rigging having an anti-friction roller acting upon a friction shoe, a holder therefor consisting of a bar furnished with projecting arms embracing the ends of the roller, said arms having flat parallel inner faces, and inclined outer faces, substantially as specified.

JOHN F. O'CONNOR.
